LIGHTING POLE

Clyde H. Clement, Phoenix, Ariz.

Application January 3, 1955, Serial No. 33,823

Term of patent 14 years

(Cl. D48—32)

FIG. 1.

FIG. 2.

FIG. 3.

Figure 1 is a side elevational view of a lighting pole showing my new design;

Figure 2 is a front elevational view thereof; and

Figure 3 is a plan view thereof.

I claim:

The ornamental design for a lighting pole, as shown.
